E 4

OF D 5,325

UNITED STATES PATENT OFFICE.

JOHN G. STRAIN, OF DELAWARE, OHIO.

DESIGN FOR A CHAIR.

Specification forming part of Design No. 5,325, dated October 24, 1871.

To all whom it may concern:

Be it known that I, JOHN G. STRAIN, of Delaware, in the county of Delaware and State of Ohio, have invented a new and original Design for Chairs; and I do hereby declare that the following is a full, clear, and exact description thereof, which will enable others skilled in the art to make and use the same, reference being had to the accompanying photograph forming part of this specification.

The nature of my design is fully represented in the accompanying photographic illustration, to which reference is made.

The distinctive character of my new design consists in the employment of "Grecian" square posts A for the backs, and round posts B for the

fronts of splint-bottom chairs, whereby these chairs are made much more desirable in respect of their general appearance than when the back posts are made round, as they have always heretofore been made. I propose to make all kinds of these chairs according to my improved design.

What I claim as my invention is—

A design for splint-bottom chairs, comprising the back posts made in the form known as the Grecian square and the front posts round.

JOHN G. STRAIN.
